UNITED STATES PATENT OFFICE.

HANS HONIGMANN, OF DULUTH, MINNESOTA, ASSIGNOR OF ONE-THIRD TO EDWARD G. HILLIARD AND ONE-THIRD TO OLIVER F. COLLIER, BOTH OF DULUTH, MINNESOTA.

SHEET-REGISTERING DEVICE FOR PRINTING-PRESSES.

Specification of Letters Patent.

Patented June 11, 1912.

1,029,445.

Application filed April 8, 1911. Serial No. 619,824.

To all whom it may concern:

Be it known that I, HANS HONIGMANN, a citizen of the United States, residing at Duluth, in the county of St. Louis and State of Minnesota, have invented certain new and useful Improvements in Sheet-Registering Devices for Printing-Presses, of which the following is a specification, reference being had therein to the accompanying drawing.

10 My invention relates to improvements in sheet registering devices for printing presses.

15 The object of my invention is to provide a device of this character which will accurately register or position the sheet of paper upon the platen of a printing press and in which the same is operated by the rocking of the platen.

20 Another object of my invention is to provide an effective device of this character having certain details of structure herein-after more fully set forth.

25 In the drawings: Figure 1 is a side elevation of a printing press platen with my improved sheet registering means attached. Fig. 2 is an elevation of the opposite side of Fig. 1. Fig. 3 is a front elevation of the complete register removed from the platen. 30 Fig. 4 is a top view of Fig. 3. Fig. 5 is a vertical section taken on the line A—B, Fig. 3. Fig. 6 is a vertical section taken on the line C—D, Fig. 3. Fig. 7 is a side elevation of the reciprocating cam. Fig. 8 is an end 35 elevation of Fig. 7. Fig. 9 is a longitudinal section of one of the registering fingers. Fig. 10 is a plan view of one end of the gripper-bar, and Fig. 11 is a side elevation of the operating finger.

40 1 represents the shaft as found in a platen printing press upon which is mounted the oscillating platen 2 common to such presses.

45 3 represents one of the inking roller carriages arms, which co-operates with the platen 2 and is indirectly connected to the shaft 1 thereof, in a manner to suitably operate the inking rollers. To the arm 3 is detachably fixed the depending inclined dog-finger 4, which, when in action, operates a portion 50 of my improved sheet registering device and while I have shown this form of attachment as the operating means, it is evident that other devices connected in a different manner to certain movable parts of the 55 press could easily be made to perform simi-

lar results without departing from the spirit of my invention.

5 and 6 represent the gripper finger bar supports, attached one at each corner of the lower edge of the platen 2, and in which the finger-bar 7 is pivotally mounted in such a manner and with suitable attachments, as commonly found on all such printing presses for raising and lowering the gripper-fingers 9, as the platen is rocked back and forth. The lower edge 8 of the bar 7 extends somewhat below the pivotal center thereof forming a cam-like member which, when in action, operates a portion of my improved sheet registering or positioning device as will be hereinafter more fully described.

10 represents the frame of the registering device having suitable holes 11 therein for attaching it to the under side of the lower edge of the platen 2, where it is firmly attached in such a manner that its movable parts properly register with the operating means above described. Upwardly extending supporting members 12, 13 and 14 are firmly fixed to the frame 10 and are designed to carry certain operative parts of the device.

One end 15 of the frame 10 depends somewhat and supports an inclined inwardly projecting shelf 16 upon which slidably operates a cam 17, its graduated edge 18 engaging the roller 19 mounted within the sliding block 20 which is fixed to the header or guide-arm shaft 21 mounted longitudinally the frame 10 and within the end 15 and the lower portion of the support 12. The cam 17 is actuated downwardly by engagement with the projecting edge 8 of the gripper 7 above described, and is retained normally in a withdrawn position by means of a suitable spring 17', one end of which is attached to the underside of the shelf 16 and the opposite end to the under side of the lower end of the cam 17. The block 20 is slidably supported intermediate the lower corner 10' of the frame 10 and the upper face of the shelf 16, as clearly shown in Fig. 5. Thus it is seen that when the gripper bar 7 is rocked downwardly as the platen is returned from press, the cam 17 will be thrust downwardly between the inner wall of the end 15 and the roller 19, which will force the roller, together with the block 20, away from the end wall 15, 110

which will impart a longitudinal movement to the shaft 21. The innermost end of said shaft 21 is screw-threaded as at 22 and carries longitudinally adjustable thereupon the vertically extending standard 23, the upper end of which is bifurcated and slidably mounted upon the fixed rod 24 mounted in the supports 12 and 14. Between the bifurcations of the standard 23 and loosely mounted upon the rod 24 is the block 25 which supports and carries the side guide 26. The block 25 is preferably rectangular in cross-section and a flat spring 27 is fixed to the side wall of the standard 23 its free end impinging against the side of the block 25 which tends to keep the guide-arm 26 at practically right angles with the standard and yet will admit of its being raised when necessary.

20 A normally expanded spring 28 surrounds the shaft 21 between a suitably fixed collar 29 upon said shaft and the side wall of the standard 12 in which said shaft is mounted, this spring keeping the shaft 21 normally thrust contrary to the active efforts of the cam 17 thus between them, imparting a reciprocating motion thereto, which operates the side guide-arm 26, as desired in registering a blank sheet for printing, said side-guide being adjustable to different sized sheets as is evident. Means for revolving the shaft 21 and thereby longitudinally positioning the side guide-arm upon the shaft for such adjustment, comprises the hand-operative crank 21' beyond the end 15. A second shaft 30 is mounted longitudinally in the frame 10 within the upright 12 and projection 31, this shaft 30 being somewhat above and a little to one side of the shaft 21.

45 A small roller 32 is mounted upon a laterally projecting pin 33 in the outer end of the shaft 30 and rides upon the tapered extension 10' of the frame 10 and is engaged by the inclined dog-finger 4, when the latter is raised and lowered by the action of the press above described.

Intermediate its bearings, the shaft 30 carries the upwardly extending member 34, the upper end of which is mounted upon and guided by the rod 24 and above said rod the member 34 is bifurcated or formed with a groove 35 therein, in which is held and operated the downwardly projecting lug 36 of the reciprocating member 37 which operates the cross-arms 38 and 39. The inner ends of these cross-arms are supported, one pivotally stationary at 38' and the other slidably and pivotally operative upon the oscillating carriage 40 which is pivotally mounted within the top of the standard 12 by means of the pin 41. The supporting member of the carriage 40 is elongated and bifurcated as at 42 in the end slidably supporting the arm 39 and grooved in such a

manner as to properly retain the slidably reciprocating member 37, which pivotally carries and operates the inner end of the arm 39. The outer ends of the cross arms 38 and 39 are pivotally fixed to a cross arm 43 which pivotally and removably supports the registering fingers 44. A pin 45 is fixed within the arm 38 intermediate its ends and extends upward through a crescent shaped slot 39' within the arm 39 which connection directs the travel of the fingers 44 in such a manner that they are extended and withdrawn in substantially a parallel position and moved slightly toward the guide-arm 26 in their homeward stroke, which is due to the single arm 39 performing the operation, it being operated back and forth by the lug 36 of the member 37 engaging the slot 35 in the member 34 and being operated thereby. The registering fingers 44 are preferably attached to the under side of the cross arm 43 by means of large flat headed screw-bolts 46 which enter suitably threaded holes through the cross-arm 43 and hold the bifurcated ends of the fingers intermediate the heads of the bolts and the under side of the cross-arm. These bolts are preferably formed with a square hole 47 longitudinal to their centers, into which a square ended wrench may be operated for adjusting the same. Tips 44' of some suitable soft material such as leather or rubber are attached to the under side of the outer ends of the fingers 44 for engagement with the paper sheets.

100 The shaft 30 carries securely fixed thereto and intermediate the supports 12 and 13 the upwardly extending elongated cam 48 rounded somewhat on top as at 48' and having a groove 49 in one side thereof and parallel with the shaft 30. Within the groove and attached to the innermost lower wall thereof is a flat leaf spring 50 which, at its free end, extends upward and beyond the opposite end of the groove as seen in Figs. 7 and 8.

105 Pivotedly attached to the upper extremity of the supporting member 13 is the arm 51 extending to a point just underneath the carriage 40 and forward of the pivotal pin 41 thereof. At its extreme innermost end the arm 51 is turned up at practically right angles and engages by contact the under side of said carriage frame as at 52 and thereby supports the carriage normally on a level plane. A small roller 53 is pivoted to the inner side of the arm 51 in such a manner as to engage the upwardly rounded surface 48' of the cam 48 when the latter is thrust toward the support 13 which, it is evident, 115 will raise the free end of the arm 51 and thereby tip up the forward or finger side of the carriage 40 lifting the fingers 44 therewith.

120 The limit of the upward stroke to the arm 130

51 is governed by the upwardly curved surface of the cam 48 and at a single stroke of the cam the arm raises and lowers to its limit, at the inner termination of which the roller is at the inner end of the groove 49 ready to allow the cam to return to its normal position without effecting the arm 51 as the roller will pass back longitudinally through the groove 49, at the termination of which latter stroke it will be elevated slightly above the entrance to the groove by the spring 50 so that a succeeding stroke of the cam 48 will cause the roller 53 to again engage the upper surface 48' of the cam 48 as above described. Thus it is seen that, as the carriage 40 is rocked upon the pivot 41, the fingers 44 will be raised and lowered therewith and made to synchronize with the reciprocations of the shaft 30 which latter motion is produced by the vertical movement of the inclined dog-finger 4 engaging the roller 32 on the shaft 30, when gaging the roller 32 on the shaft 30, when the inking roller arm 3 is raised and lowered by the action of the printing press. A normally contracted spring 51' is attached at one end to the hub of the member 34 and the opposite end to the frame 10, whereby the shaft 30 is normally held with the roller 32 engaging the dog-finger 4, whereby the rectrocation is produced.

The dotted line 52 in Fig. 4 represents approximately the position of a blank sheet of paper upon the face of the platen ready to be registered or positioned by the fingers 44, which engage it upon its upper surface and draw it to position when the platen is rocked forward, the dog-finger 4 and the bar-cam 8 operating the registering device and guide arm as above described whereby an accurate automatic registering of the paper is accomplished.

The operation of the device is as follows: The printing press is found normally with the shaft 1, platen 2, ink roller carriage arm 3 and gripper finger bar supports 5 and 6 supporting the finger-bar 7, which carries the gripper fingers 9, all of which are made to synchronize in operation and which form no part of my invention, they being common to all such presses. The most convenient place of attachment and operation of my improved sheet positioning or registering device is at the lower inner edge of the platen 2 and it is there shown in the drawings and as operated, one portion by the dog-finger 4 attached to the arm 3 and the other portion by the cam-like projection 8 of the finger bar 7 as above described. When a sheet of blank paper is placed upon the platen and the latter goes to press, the arm 3 descends and carries with it the inclined dog-finger 4, which latter engages the roller 32 on the shaft 30 and forces the latter longitudinally, which operates simultaneously the cam 48 and the member 34. The

cam 48 raises and lowers the finger 51 as it goes back and forth as above described, which rocks the carriage 40 up and down upon its pivotal pin 41, while at the same time the member 34 is sliding back and forth the inner end of the lever 39 upon the bifurcated end 42 of the rear side of the carriage 40 by engaging the lug 36 of the slide 37, which is pivotally attached to the inner end of the lever 39, which results in the outer ends of the fingers or fingers 44 being raised and lowered vertically and drawn in and out horizontally by the reciprocation of the shaft 30, the reverse motion of the shaft 30 being produced by the spring 51', as described. The operation of the fingers 44 is timed to properly receive the sheet and position it just previous to printing. The position of the blank sheet is governed longitudinally by the side guide arm 26, which is made to synchronize with the operation of the printing press by being attached to the shaft 21 through the medium of the standard 23, which shaft 21 is made to reciprocate by the cam-like projection 8 of the bar 7 engaging the sliding cam 17 and thereby forcing the shaft 21 in one direction while the spring 28 operates it in the opposite direction, thus producing a slight movement of the arm 26 which helps to guide the sheet and properly position it for printing.

Having thus described my invention, what I claim and desire to secure by Letters Patent is:

1. The combination with a platen press, of two longitudinally movable shafts carried by the platen, a guide carried by one shaft, a registering means carried by the other shaft, and means operated by the press for moving first the shaft carrying the guide and then the shaft carrying the registering means, substantially as shown and described.

2. The combination with a platen press, of two longitudinally movable shafts carried by the platen, a guide carried by one shaft, a registering means carried by the other shaft, and means operated and timed with the press to move the shafts longitudinally in successive order.

3. The combination with a platen press, of a shaft longitudinally movable upon the platen, a guide carried by said shaft and extending in a plane with the platen, means operated by the rocking of the platen for moving said guide transverse the platen, a second shaft longitudinally movable upon the platen, means operated by the rocking of the platen for moving said shaft longitudinally and registering means secured on the shaft for registering the blank sheets of paper with the guide upon the platen after they have been fed thereto.

4. The combination with a platen printing press, of a frame secured to the lower edge of the platen, two longitudinally mov-

- able shafts carried by the frame, a guide carried by one of said shafts, means operated by the rocking of the platen for moving the guide transverse the platen and registering 5 means carried by the other shaft for registering the blank sheets of paper with the guide upon the platen after they have been fed thereto.
5. The combination with a platen printing press, of a frame secured to the lower edge of the platen, two longitudinally movable shafts carried by said frame, a guide carried by one of said shafts, registering means carried by the other shaft and means 10 operated by the rocking of the platen for operating said guide and registering means.
6. The combination with a platen printing press, of a frame removably secured to the lower edge of the platen, two longitudinally 15 movable shafts carried by the frame, a guide carried by one of said shafts, registering means carried by the other shaft, means operated by the rocking of the platen for moving the said shafts in the frame, whereby the 20 sheets of paper are properly positioned upon the platen.
7. The combination with a platen printing press, of a frame secured thereto, a longitudinally movable shaft carried by the frame, 25 a guide carried by said shaft, a second shaft longitudinally movable upon the frame, registering means carried by the said second shaft, and means operated by the rocking of the platen for first moving the guide shaft 30 to bring the guide in the proper position upon the platen and secondly moving the registering shaft to cause the sheets of paper to register with the guide upon the platen.
8. The combination with a platen printing press, of a plate secured to the lower edge of the platen, a shaft longitudinally 35 movable upon the plate, a guide carried by said shaft and extending in a plane with the platen, means operated by the rocking of the platen for moving said guide transversely of the platen, a second shaft longitudinally movable upon the plate, means operated by the rocking of the platen for moving said shaft longitudinally, and registering 40 means operated by the shaft for registering the blank sheets of paper with the guide upon the platen after they have been fed thereto.
9. The combination with a platen printing press, of a plate secured to the lower edge thereof, a shaft longitudinally movable upon the plate, a guide carried by said shaft, means for adjusting the guide on said shaft, a cam-shaped plate carried by the shaft, a cam 45 carried by the platen and engaging the cam-shaped plate for moving the shaft longitudinally and moving the guide transverse the platen, a second shaft mounted upon the platen and longitudinally movable, means 50 carried by the platen for moving said shaft longitudinally, and means operated by said second shaft for registering the blank sheets of paper with the guide upon the platen after they have been fed thereto.
10. The combination with a platen printing press, of a plate secured to the lower edge thereof, a shaft longitudinally movable on said plate, a guide adjustable on said shaft and movable transversely of the platen, a cam shaped plate carried by the shaft, a cam carried by the platen and engaging the cam-plate and moving the shaft longitudinally on the plate, a second shaft longitudinally movable upon the plate, means operated by the rocking of the platen 55 for moving said second shaft longitudinally upon the plate, and toggle levers operated by the longitudinal movement of the said second shaft for operating the fingers for engaging the sheets of paper upon the platen 60 and registering them with the guide.
11. The combination with a platen printing press, of a plate secured to the lower edge of the platen, a shaft longitudinally movable upon said plate, a guide carried by 65 said shaft, means for adjusting said guide upon the shaft, means operated by the rocking of the platen for moving said shaft longitudinally, a second shaft mounted upon the plate, a roller carried by the outer end 70 of said shaft, an arm carried by the platen and engaging said roller and moving the shaft longitudinally, cross-arms operated by the inner end of the second shaft and registering fingers carried by the outer end of 75 said shaft, for registering the blank sheets of paper with the guide after they have been fed to the platen.
12. The combination with a platen printing press, of a plate secured to the lower edge of the platen, a shaft longitudinally movable on said plate, a guide screwed upon said shaft, means for rotating the shaft for adjusting the guide thereon, means operated by the rocking of the platen for longitudinally moving the said shaft, a second shaft mounted upon the plate, means operated by the rocking of the platen for moving said second shaft longitudinally upon the plate, cross-arms operated by the inner end of the 80 second shaft, gripping fingers carried by the outer ends of the toggle levers and engaging the blank sheets of paper upon the platen 85 and registering them with the guide, and means for vertically rocking said toggle levers, whereby the gripping fingers are raised and lowered upon the blank sheets of paper on the platen.
13. The combination with a platen printing press, of a plate secured to the lower edge of the platen, a spring held shaft longitudinally movable upon the said plate, a guide longitudinally adjustable upon the shaft, a second shaft longitudinally movable upon the plate, a frame horizontally pivoted 90

upon the plate, cross-arms pivoted upon said frame, gripping fingers carried by the outer ends of the toggle levers and adapted to engage and register the blank sheets of paper with the guide upon the platen, means carried by the second shaft for operating said toggle levers, and means carried by the second shaft for rocking the frame upon its horizontal pivot, substantially as shown and described.

14. The combination with a platen printing press, of a plate secured to the lower edge of the platen, of a guide horizontally movable upon said plate, means operated by the rocking of the platen for moving said guide, a shaft longitudinally movable upon the plate, means operated by the rocking of the platen, for moving said shaft longitudinally, a frame horizontally pivoted upon said plate, toggle levers carried by said frame, positioning fingers carried by the outer ends of the toggle levers, means carried by the shaft for operating said toggle levers, a pivoted member engaging the frame, and means operated by the shaft for raising and lowering said pivoted member, whereby the frame is rocked upon its pivot to raise and lower the positioning fingers.

15. The combination of a platen printing press, of a plate secured to the lower edge thereof, a spring pressed shaft horizontally movable upon said plate, a guide screwed upon the said shaft, means whereby the shaft may be rotated for adjusting the guide upon the shaft, a cam plate carried by the shaft, a cam carried by the platen and engaging the cam plate for longitudinally moving the shaft upon the rocking of the platen, a second shaft horizontally adjustable on the plate, a roller carried by the outer end of said shaft, means carried by the platen for engaging said roller and moving the shaft longitudinally, a frame horizontally pivoted upon said plate, toggle levers carried by said frame, positioning fingers

carried by the outer end of said toggle levers, means carried by the inner end of the second shaft for operating said toggle levers, and means carried by the inner end of the second shaft for rocking the frame 50 on its horizontal pivot.

16. The combination with a platen printing press, of a plate secured to the lower edge thereof, a spring-held shaft horizontally adjustable on said plate, a guide 55 screwed upon said shaft, means whereby the shaft may be rotated for adjusting the guide longitudinally upon the shaft, a cam plate operated by a cam carried by the platen for moving the shaft longitudinally upon the 60 plate, a second shaft longitudinally movable upon the plate, a horizontally pivoted roller carried by the shaft, an arm carried by the platen for engaging said roller and moving the second shaft longitudinally, a 65 frame horizontally pivoted upon the plate, toggle levers pivoted upon the frame, registering fingers carried by the outer ends of the toggle levers, an arm carried by the said second shaft and engaging the inner 70 end of the toggle levers, for operating the same, a horizontally pivoted member supporting the frame, and an upwardly projecting member carried by the inner end of the second shaft and having a rounded upper face supporting the horizontally pivoted member, whereby the longitudinal movement of the said second shaft will raise and lower the horizontally pivoted member and rock the horizontally pivoted frame for raising and lowering the positioning fingers 75 whereby the blank sheets of paper are properly positioned upon the platen in respect to the guide.

In testimony whereof I hereunto affix my 85 signature in the presence of two witnesses.

HANS HONIGMANN.
